UNITED STATES PATENT OFFICE.

JOSEPH T. HICKMAN, OF WASHINGTON, DISTRICT OF COLUMBIA.

DUAL-CONTROL APPARATUS.

Application filed June 30, 1924. Serial No. 723,271.

My invention relates to radio receivers, transmitters and other electrical or mechanical devices requiring the operation of two or more controls substantially in unison with each other, and has for an object the providing of an efficient means for operating a plurality of controls.

A further object of my invention is to provide a means whereby two or more controls may be operated separately or in unison.

With these and other objects in view, the invention consists in the combination, construction and arrangement of parts as will hereinafter be fully described.

Reference is to be had to the accompanying drawings, forming a part of this specification in which like reference characters indicate corresponding parts throughout the several views, and in which

Figure 1 is a broken front view of the panel of a radio instrument.

Figure 2 is a sectional view of my invention.

Figure 3 is a perspective view of the clutch members.

Figure 4 is a perspective view of the pulley.

Figure 5 is a broken rear view of the panel of a radio instrument, showing the pulleys and belt.

Heretofore, when tuning a radio receiver containing several controls, it has been the practice to operate each one separately. While this procedure can still be followed when using my invention, I have made it possible to operate all controls with any single one of them.

Referring to the drawings (1) is a dial, graduated so that the setting may easily be determined. Attached to the dial in any suitable manner is a knob (2) preferably of hard rubber. The knob has an annular space through its center in which is closely fitted a metallic member (3), also attached to the dial (2). Member (3) contains a recessed annular space in which hollow shaft (4) is free to slide when pressure on knob (2) is exerted. Hollow shaft (4) contains a slot (5), through which pin 6, securely

attached to shaft (7), extends. When knob (2) is rotated, pin 6 engages the sides of slot (5), thereby causing shaft (7), which passes through panel 9 and to the inner end of which are attached the movable plates (8), to rotate. Knob (2) and member (3) are securely clamped to shaft (4) by clamping screw (12).

Knob (2) is kept in an outward position, as illustrated in Figure 2 by spring 10. The tension on this spring may be adjusted by screw (11) which is threaded through the end of member (3). Between spring (10) and screw (11) is a washer (15) which prevents the spring grabbing the screw and insures smooth running.

The inner end of shaft (4) contains a clutch cone (13), which engages pulley 14, through tension of spring (10). When inward pressure is applied to knob (2), spring (10) is compressed, and clutch cone (13) is allowed to release from pulley (14), thereby permitting separate adjustment of the control.

The pulley (14), which is free to rotate about shaft (4) contains grooves (17) in which the belt (16) runs. Either a single belt wrapped twice about the intermediate pulley or separate belts between the pulleys, may be used. By turning the knob (2) of any control, it being in its outward position, all controls are turned in unison.

While I have described my invention as applied to a radio receiver, it can be applied with equal efficiency to a transmitter or other electrical or mechanical device requiring unison of movement and it is to be understood that the above description and accompanying drawings comprehend only the general and preferred embodiment of my invention and that various changes in details of construction, proportion and arrangement of parts may be made within the scope of the appended claims without sacrificing any of the advantages of my invention.

Having described my invention I claim:

1. A mechanism of the class described including, in combination, a plurality of rotat-

able members, pulleys rotatably mounted with the members, cables trained over the pulleys, elements for operating the rotatable members, and clutches controllable by the elements for rotating the pulleys.

2. A mechanism of the class described including, in combination, a plurality of rotat-

able members, pulleys rotatably associated with the members, means operatively connecting the pulleys, elements for operating the rotatable members and clutches controllable by the elements for rotating the pulleys.

JOSEPH T. HICKMAN.
